Des. 226,873
Patented May 8, 1973

226,873

PRE-FABRICATED SAUNA THERAPY BATH UNIT

Cleo D. Mathis, 1808 Potrero Ave.,
South El Monte, Calif. 91733

Filed Mar. 26, 1971, Ser. No. 128,653

Term of patent 14 years

Int. Cl. D23—02; D24—99
U.S. Cl. D83—1 C

FIG. 1.

FIG. 2.

FIG. 3.

FIG. 4.

FIG. 5.

FIG. 6.

FIG. 7.

FIG. 8.

FIG. 9. ← 14

FIG. 14.

FIG. 10.

FIG. 11.

FIG. 12.

FIG. 13.

FIG. 15.

FIG. 1 is a front elevational view of a pre-fabricated sauna therapy bath unit embodying my new design;

FIG. 2 is a side elevational view of the same, the opposite side being identical;

FIG. 3 is a top plan view of the same;

FIG. 4 is a rear elevational view of the same;

FIG. 5 is a bottom plan view of the same;

FIG. 6 is a sectional view taken on line 6-6 of FIG. 1 with the right side of the seat broken away to disclose the structure therebeneath;

FIG. 7 is a sectional view taken on line 7-7 of FIG. 1;

FIG. 8 is a sectional view identical to FIG. 7 on a reduced scale showing a modified embodiment of the unit;

FIG. 9 is a front elevational view of another embodiment of pre-fabricated sauna bath unit embodying my new design;

FIG. 10 is a rear elevational view of the same on a reduced scale;

FIG. 11 is a side elevational view of the same on a reduced scale, the opposite side being identical;

FIG. 12 is a top plan view of the same on a reduced scale;

FIG. 13 is a bottom plan view of the same on a reduced scale;

FIG. 14 is a small enlarged sectional view of the same taken on line 14-14 of FIG. 9;

FIG. 15 is a sectional view of the same taken on line 15-15 of FIG. 9.

I claim:

The ornamental design for a pre-fabricated sauna therapy bath unit, substantially as shown and described.
